(57) **CLAIM**

We claim the ornamental design for a cover for a pie pan, as shown and described.

DESCRIPTION

FIG. 1 is a top front side perspective view of the cover for a pie pan;

FIG. 2 is a side view of the design shown in FIG. 1;

FIG. 3 is a front side view of the design shown in FIG. 1;

FIG. 4 is a bottom view of the design shown in FIG. 1; and,

FIG. 5 is a top view of the design shown in FIG. 1.

The subject matter shown in dashed lines, and any surfaces of the design not shown, including interior surfaces, form no part of the claimed invention.
